FIRE DETECTING DEVICE

Vernon Durbin, Newton, Mass., assignor to The Holtzer-Cabot Electric Company, Boston, Mass., a corporation of Massachusetts

Application August 31, 1934, Serial No. 742,264

24 Claims. (Cl. 200—138)

This invention relates to heat responsive devices and especially to fire detecting, alarm-initiating devices.

The fire detecting device embodying the present invention is adapted to be located within the zone to be protected in thermal relation with the ambient atmosphere and so arranged as to be responsive to and operated by an abnormal temperature condition of the atmosphere to control an alarm circuit as by either making or breaking the circuit, thereby to actuate some suitable remotely located alarm device.

Since the device may remain in an unoperated condition over a long period of time and yet, to perform its function when called upon to do so, must be maintained constantly in operative condition, an object of the present invention is to enclose the operating parts of the device including the heat actuated element within an enclosing casing that is sufficiently tight to exclude from the operating parts dust and foreign matter that might impair or prevent the operation of the device and at the same time provides an effective transfer of heat from the external atmosphere to the internal heat actuated element.

A further object of the invention is the provision of a fire detecting device including a casing having therein a heat actuated element, the casing having a member of good heat conduction, as a metal cover, that is exposed to the ambient atmosphere and serves to transmit heat therefrom to the heat actuated device.

A further object of the invention is the provision of a fire detecting device having a thermostatic bimetal strip wound in spiral form as the heat actuating element, the element being enclosed within a casting having a cover of good heat conducting material and the element resting on edge loosely on the cover so that it can move freely in response to the heating thereof and so that the heat of the ambient atmosphere is transmitted by conduction through the cover to the thermostatic strip.

Complete protection against fire in a zone supervised by a device of the present invention requires that the device be responsive both to a predetermined elevation of temperature and also to an excessive rate of rise of temperature regardless of the elevation thereof. Hence a further object of the present invention is the provision of a fire detecting device having an improved construction that includes two heat actuated elements that cooperate to respond to a predetermined elevation of temperature and also to an abnormal rate of rise thereof.

An additional object of the invention resides in the use of one circuit controlling device for both heat actuated elements so that the operation of either element or both conjointly results in the proper operation of the circuit controlling device.

A yet further object of the invention is the provision of a fire detecting device having two heat actuated elements arranged to cause the device to respond both to a predetermined elevation of temperature and an abnormal rate of rise of temperature, and a casing enclosing both elements with provision whereby one element receives heat from the ambient atmosphere more rapidly than the other element and particularly wherein the casing has a part of good thermal conductivity arranged in contact with one of said heat actuated elements and wherein the other element is thermally insulated to an appropriate degree from the first element and from the conducting part of the casing.

As has been stated above a fire detecting device of the type with which the present invention is concerned is required to stand idle for long periods of time and yet must operate satisfactorily when subjected to a dangerous temperature condition. Heretofore the circuit controlling contacts have been a source of uncertainty. If the circuit is normally open, so that the contacts are maintained separated for a long period of time, dirt and oxide is liable to accumulate on the contact faces and prevent the proper closing of the circuit when the contacts are brought together. If the circuit is normally closed, so that the contacts are normally engaged, they are liable to stick together and will not separate when required to do so. Hence a further object of the invention is the provision of a fire-detecting device wherein the circuit controller has its contacts enclosed within a sealed casing that is evacuated or contains an inert atmosphere so that complete reliability of operation over indefinitely long periods is assured. Specifically the circuit controller is of the mercury contactor type wherein the spaced circuit electrodes are sealed within an evacuated casing or one containing an inert atmosphere and wherein a mobile body of mercury is caused to bridge and also disconnect the electrodes upon the tilting of the casing in opposite directions, the casing being tilted by movement of the heat actuated element.

A further object of the invention is the provision of a fire detecting device including two heat actuated elements having movable ends on and between both of which a carrier for the contactor

casing is fulcrumed, the arrangement being such that the movement of either one element relative to the other causes the tilting of the carrier and the operation of the contactor.

5 A yet further object is generally to improve the construction of fire detecting, alarm-initiating devices in details that are important from the standpoint of reliability of operation and of economical manufacture and assembly and freedom from unauthorized manipulation.

10 Fig. 1 is a side elevation of the fire detecting device of the present invention in installed position.

Fig. 2 is a plan view of the device of Fig. 1.

15 Fig. 3 is an enlarged plan view of the device of Fig. 1 with the cover removed.

Fig. 4 is a section taken along line 4—4 of Fig. 3.

20 Fig. 5 is a side elevation of the device with the casing partly broken away to illustrate the circuit controller which as here shown is in an unoperated or open circuit condition.

25 Fig. 6 is a sectional view similar to Fig. 4 but showing a modification providing increased heat insulation between the two heat actuated elements.

Fig. 7 is a side elevation of the device with the casing partly broken away to illustrate the manner of locking the cover against rotation.

30 Fig. 8 is a perspective view of an adjustable stop member for one of the heat actuated elements.

35 Fig. 9 is a diagram of the circuit controller illustrating the manner in which the controller operates when the top heat actuated element is stationary and the lower heat actuated element is moving under the influence of heat.

40 Fig. 10 is a view similar to Fig. 9 but illustrating the position of the circuit controller when both heat actuated elements are moved at about the same rate.

45 Fig. 11 is a view similar to Fig. 10 but illustrating the position of the circuit controller after the top heat actuated element has been arrested in advanced position and the lower heat actuated element has moved further to actuate the circuit controller.

50 Fig. 12 is an enlarged plan view of a portion of a heat actuated element and illustrating the bimetal construction thereof.

55 The fire detecting device embodying the present invention comprises generally a casing 14 containing the operative elements of the device. The device is adapted to be secured in any desired location in a room preferably on the ceiling 16 thereof and may be attached to and form the cover of a junction box 18 through which conductors 20 of an alarm circuit are extended. The casing comprises a base 22 preferably circular in configuration having a flat top face 24 and composed of some suitable electrically insulating material as a molded artificial resin. The casing is provided with a generally circular recess 26 open at the bottom and adapted to receive the operating elements of the device. The base is formed with an integral ledge 28 which projects into the recess from one side thereof and carries sets of circuit terminals 30 and 32. A plate 34 of suitable heat insulating material is secured to the top face of said ledge 28 preferably removably by screws 36 and projects into the recess 26 in spaced relation with the top wall 24 of the recess. Said plate at its inner end terminates in a circular heat insulating disc 38 which is disposed coaxially of the recess and is integral with the plate and is of suitable area and thickness to

provide a suitable time lag or delay in the operation of one heat-actuated element over the other, as will be explained hereinafter. A cylindrical boss 40 is integral and coaxial with and projects below said disc 38 and partially externally of the recess and constitutes a support and anchorage for the inner end of the lower heat actuated element 42. Said element 42 comprises a thermostatic strip consisting of two metals 42a and 42b, see Fig. 12, having dissimilar coefficients 10 of heat expansion secured together back to back. Said strip is formed into spiral configuration and has a radially inwardly extended fixed inner end 44 and a radially outwardly extended movable end 46. The inner end is received within a longitudinally extended slot in the boss 40 and thereby is anchored against rotation. The first or innermost convolution 48 of the spiral is preferably of circular configuration so that it overlaps and presses against the inner end of the strip and thereby holds it in the slot against escape therefrom without the necessity for other securing means. The open recess 26 of the base is closed by a cover 50 which preferably is cup shaped having a flat bottom wall 52 and an upstanding circular side wall 54 which closely fits within the recess of the base sufficiently tightly to exclude dust and other deleterious foreign matter from entering the casing. The bottom wall 52 of the cover overlies and bears against the end face of the hub 40 and is secured thereto by a screw 56 which is screw-threaded in the boss, the screw having an enlarged thin head 58 which overlies the cover and has a pair of wrench receiving apertures 60 therein in which the prongs of a suitable wrench can be inserted for the purpose of rotating the screw. After the screw has been inserted it is locked in position by a pin 62 which is passed through one of said wrench holes 60 and driven into the end of the boss 40. A rating plate 64 is then sprung permanently into a cup shaped recess formed in the outer face of the head of the screw and overlies the pin 62 and permanently prevents its removal so that the screw can not be removed subsequently by an unauthorized person. The cover 50 is locked against rotation on the screw 56 additionally to the pin 62 by a tongue 63 formed at the edge of the supporting plate 34, which tongue is located within a notch 65, see especially Fig. 7, formed in the edge of the side wall 54 of the cover, the tongue thereby acting as a key to prevent the cover from rotating and loosening the screw 56.

70 The cover 50, in accordance with this invention, is composed of some metal, as copper, that has high thermal conductivity so that the rate of heat transmission through it from the atmosphere surrounding the device is rapid. The heat actuated element 42 has its lower face substantially flush with the top of the boss 40 and hence rests upon and is in direct metallic contact with the inner face of the metal wall 52 of the cover 50. The heat actuated element is supported only at its center and, due to its spiral configuration and the long length of the strip composing it, is axially flexible so that it can rest by its weight upon the cover and yet expand and contract freely while in contact with the cover. Due to the metallic contact between the element and the heat-collecting cover the heat of the ambient atmosphere is transmitted through the cover rapidly to the heat actuated element whereby to cause it to assume an expanded condition dependent upon the temperature of the atmosphere. A second heat actuated element 66 which may be and pref-

erably is substantially identical with the lower heat actuated element 42 is disposed in the upper part of the recess 26 of the base on the top side of the insulating plate 34. A metal stud 68 is 5 molded into the disc 38 of said insulating plate and projects upwardly in the axial line of the recess 26. A metal hub 70 is received rotatably loosely on said stud and is in engagement with the inner end of the upper heat actuated element 10 in the same way that the boss 46 engages the inner end of the lower element 42. A washer 12 is disposed on top of the stud and a nut 74 is screw-threaded thereon to exert pressure against the washer and hub and clamp the hub upon the insulating supporting plate 34. The top face of 15 the hub is provided with a pair of diametrically opposed slots 76 and the washer is formed with corresponding slots adapted to receive projections of a tool to hold the hub and hence the heat actuated element 66 against rotation while the nut 74 is being rotated to clamp the hub in adjusted position. The stud 68 and the nut 74 thereon projects upwardly through a hole 78 in the top wall 24 of the insulating base so that the 20 setting of the upper heat actuated element can be made readily. The upper heat actuated element is spaced from the lower element and from the cover 50 and is insulated from both by the heat insulating discs 38 and hence receives heat 25 by radiation from the cover more slowly than the lower element 42. When the device is subjected to a rise in temperature that is so slow that the rise is not ordinarily caused by a fire condition the temperature of the top element closely follows the increase in ambient temperature so that 30 the two elements expand at about the same rate and thus do not become operative to initiate a warning signal. When, however, the ambient temperature rises so rapidly as to indicate the 35 probability of a dangerous fire condition the lower heat actuated element becomes heated faster and thus expands more rapidly than the upper element and hence causes the control of the signal circuit to initiate a warning signal. The difference in the rate of heating of the two elements and hence the time lag of expansion between them in response to a rise of temperature can 40 be varied by varying the thickness of the insulating supporting plate 34 and by the amount of 45 area of said plate interposed between the elements. In Fig. 6 a modified form of plate 34a is illustrated wherein the disc 38a is approximately as large in diameter as the diameter of the spiral heat actuated elements 42 and 66 there- 50 by to provide a greater time lag of heating and operation of the two elements than is provided by the smaller area of the disc illustrated in 55 Fig. 4.

The two actuated elements are arranged independently and also conjointly to control a circuit controller. Said circuit controller is of the so-called mercury contactor type and comprises an elongated cylindrical sealed enclosing casing 80 composed of glass or the like having its circuit terminals 82 and 84 sealed in one end of the tube and projecting in spaced relation into the interior thereof. The tube contains a small mobile body of mercury 86 that, when the tube is inclined in one direction, occupies one end of the tube and 70 is in contact with and electrically bridges the terminals and, when the tube is inclined in the opposite direction, leaves the terminals and runs into and occupies the other end of the tube. The tube is evacuated or contains a gas that is inert 75 with respect to the mercury and the electrodes

so that these elements remain clean and in operative condition indefinitely. With this type of circuit controller the proper operation thereof is assured even after years of inactivity and thus the fire detecting device is reliable to a degree not 5 readily attained by the usual type of circuit controller having exposed separable solid contact members. The circuit controller is mounted in a carrier which comprises a vertically disposed insulating block 88 having a hole through the middle thereof in which the tube 80 is frictionally retained. The top and bottom ends of the block are provided with V shaped notches 90 in which the movable ends 46 and 92 of the lower and upper heat actuated elements respectively are located. The confronting edges of said ends engage and fulcrum in the bottoms of the notches and bear with a slight tension against the block by the inherent axial resiliency of the heat actuated 10 elements due to the spiral configuration thereof. 15 The ends of said elements are retained in said notches against accidental displacement therefrom by retaining pins 94 which are frictionally retained in the carrier 88 and traverse the notches and pass loosely through relatively large 20 clearance holes in the ends 46 and 90. The circuit terminals 82 and 84 are electrically connected to conductors 96 and 98 which are attached to the carrier 88 and then extend loosely 25 to the terminals 30 and 32 respectively of the device. The conductors are sufficiently slack between said carrier and the terminals so as to 30 permit unrestricted angular movement of the heat actuated elements and the tilting of the controller within the required range. The angular 35 displacement of the free end 92 of the upper heat actuated element 66 is limited for the purpose of defining the elevated temperature at which the device shall operate its circuit controller. To this end the device is provided with 40 a stop member or arm comprising a plate 100, see Figs. 3, 4 and 8, which is capable of angular movement about the stud 68 under the hub 70 and is clamped in set position by said hub against the supporting plate 34. Said plate 100 is provided 45 with an upwardly extended end portion 102 which bears frictionally against the inner face of the wall 36 of the base 22 by the inherent resiliency of the plate, thereby cooperating with the clamping action of the hub 70 in holding the plate in set 50 position. The end 102 is provided with an extension 104 that is adapted to be engaged by the free end of the upper heat actuated element or, more precisely, by the upper end of the circuit controller carrier 88 whereby to limit the expansion 55 movement of the upper heat actuated element and thereby effect the operation of the circuit controller in response to an elevation of temperature determined by the setting of said stop arm.

The operation of the device is essentially as follows: The normal position of the heat actuated elements can be as illustrated in Fig. 3 and in the full lines of Fig. 9. When the ambient temperature rises both heat actuated devices are influenced by the increase of temperature and are caused to expand in a direction to increase the lengths of their spirals. If the rise of ambient temperature is relatively rapid the lower heat actuated device expands more rapidly than the upper one since it is more directly influenced by the heat while the upper element, being relatively insulated from the heat, expands more slowly. The result ultimately is that the lower 70 end of the carrier 88 advances more than the up- 75

per end thereof so that the upper end fulcrums upon the free end of the upper element and causes the tilting of the tube 80 in a direction to cause the mercury to run into the terminal end of the tube and bridge the terminals 82 and 84 and thereby complete the circuit through said terminals to effect the initiation of an alarm signal. If the rise of temperature is so slow that both heat actuated elements expand practically simultaneously the circuit controller will be advanced in the manner indicated in Fig. 10 but without change in the relative disposition of the free ends of the elements so that the circuit controller will not be tilted and operated. If the slow rise of temperature continues until the temperature elevation is sufficiently great, however, the advance of the free ends of the elements will continue until the upper end of the carrier 88 is brought into engagement with the projection 104 of the arm 100. Further advance of the top of the upper element is thus prevented. The lower element, however, will continue its advance and in doing so will tilt the tube 80 into the position illustrated in Fig. 11, thereby causing the mercury body to run into the lower end of the tube and bridge the circuit terminals 82 and 84 in the manner above described, thereby initiating an alarm signal as a result of the elevation of temperature regardless of the slow rate of increase 30 of temperature.

I claim:

1. A fire detecting device including a pair of thermo-responsive elements, a dust tight casing enclosing said elements and isolating them from the ambient atmosphere, said elements being equally freely exposed to the atmosphere within said casing, and a signal initiating device associated with said elements, said casing having a heat-transmitting wall exposed to the atmosphere surrounding said casing and adapted to become heated by exposure to the atmosphere and heat the interior of said casing, and one of said elements being disposed nearer than the other element to said wall so that it is more immediately responsive to the atmosphere externally of said casing.

2. A fire detecting device including an enclosing casing having a heat conducting wall exposed to the atmosphere surrounding said casing, a pair of heat responsive elements located within said casing one adjacent and the other remote from said heat conducting wall and receiving heat from the atmosphere only by transmission through the material of said wall, said elements being equally freely exposed to the atmosphere within said casing, heat insulating means carried by the casing independently of and interposed between said elements, and signal initiating means associated with said elements.

3. A fire detecting device comprising an enclosed casing having a heat conducting wall exposed to the atmosphere externally of the device for transferring heat from the exterior to the interior of the casing, a pair of thermo-responsive elements located within said casing and both being approximately equally freely exposed to the atmosphere within the casing, one of said elements being adjacent and the other remote from said wall, and a heat insulating barrier interposed 70 between said wall and said more remote element.

4. A fire detecting device comprising a support having a projecting stud, a hub angularly movable on said stud having a longitudinally directed slot in its outer face, a thermostatic spiral sur-

rounding and carried by said hub having a free outer end and an inwardly directed end that is located in said slot, said slot opening into the end face of said hub, a washer on said stud upon said end face and overlying said slot, and a clamping nut screw-threaded on said stud and bearing on said washer.

5. A fire detecting device as defined in claim 4, said hub and washer being larger in diameter than said nut and having registering wrench engaging notched portions by which said hub and the thermostatic spiral carried thereby can be shifted angularly on said stud whereby said spiral and nut may be relatively rotated while one is held stationary.

6. A fire detecting device comprising a support having a projecting stud, a thermostatic spiral having an inner hub rotatable on said stud, a clamping nut screw-threaded on said stud and bearing on said hub, said spiral having a free outer end, signal initiating means associated with said outer end, and a limit arm located between said support and hub and angularly shiftable on said stud having an end disposed in the path of travel of the free end of said spiral.

7. A fire detecting device comprising an enclosing casing having a recess, a support in said recess having a boss outstanding from said support in one direction and a stud outstanding from said support in the opposite direction, a thermostatic spiral carried by said boss, a second thermostatic spiral having a hub rotatable on said stud, said spirals having free outer ends, a circuit controller associated with said free ends, and a resilient limit arm pivoted on said stud between said hub and support having a free end bearing yielding upon and movably over the bottom of said recess in the path of movement of the free end of one of said thermostatic spirals to limit the movement of the free end of one only of said spirals, whereby to effect the operation of said circuit controller, and a nut screw-threaded on said stud which clamps said arm in set position between said support and hub.

8. A fire detecting device comprising a support, a thermostatic spiral having its inner end pivotally mounted on said support and having a free outer end, a limit arm pivotally mounted on said support concentrically with said spiral having as end portion disposed in the path of movement of the free end of said spiral, clamping means for securing both said spiral and said arm in predetermined adjusted positions, means permitting angular adjustment of said arm and spiral each without displacement of the other, and signal initiating means associated with the free end of said spiral.

9. A fire detecting device comprising a supporting plate, a support therefor engaged with one end of said plate, the other end of said plate having a boss projecting in one direction laterally therefrom and a projecting stud that is co-axial with said boss and projects in the opposite direction therefrom, a thermostatic spiral having its inner end carried by said boss and having a free outer end, a second thermostatic spiral having an inner hub rotatable on said stud and having a free outer end, a nut screw-threaded on said stud and bearing on the end of said hub to clamp it to said supporting plate, and signal initiating means associated with the free ends of said spirals.

10. A fire detecting device comprising a base having a recess, a supporting plate fixed to said base having a part that projects into said recess

and has a boss, a thermostatic spiral in said recess on said boss and having a free outer end, a metal cover plate for said recess parallel to, and in contact with the edge of the convolutions of said spiral, means securing said plate in the aforesaid relation to said boss, and signal initiating means associated with the free end of said spiral.

11. A thermo-responsive device comprising two thermo-responsive members responsive at different rates when subject to the same operating temperature and movable in the same direction by substantially the same amount when the operating temperature is slowly changing and movable by substantially different amounts when the operating temperature is rapidly changing, and a circuit controller associated with said members and movable with both of them and also with any one of them, said circuit controller having means by which its movements with both members moving in the same direction by the same amount is ineffective to control a circuit and by which it is effectively operated only when the position of one member changes by a predetermined amount with respect to the other member.

12. A fire detecting device comprising two movable thermo-responsive members responsive at different rates to a common temperature, a carrier disposed between and fulcrumed on both members and arranged to tilt when one of said members becomes displaced more than the other member and to be bodily displaced without tilting when both members are displaced by the same amount in the same direction, and a mercury contactor carried by and tilttable with said carrier.

13. A fire detecting device comprising two thermostatic strips having fixed ends and free ends that are movable in the same direction when said strips are subjected to elevated temperature, a tilttable carrier disposed between and fulcrumed on both free ends of said strips and adapted to tilt upon said strips when one strip advances ahead of the other, a circuit controller responsive to the tilting of said carrier, and a stop member for limiting the movement of one of said strips.

14. A fire detecting device comprising two thermostatic strips having fixed ends that are movable in the same direction when said strips are subjected to elevated temperature, a tilttable carrier disposed between and fulcrumed on both free ends of said strips and adapted to tilt upon said strips when one strip advances ahead of the other, a circuit controller responsive to the tilting of said carrier, a stop member for limiting the movement of one of said strips, and means for relatively insulating the strip of restrictive movement from the heat that influences the other strip.

15. A fire detecting device comprising two concentric parallel thermostatic spirals having free ends, a carrier disposed between and fulcrumed on both free ends, said carrier being movable with said free ends without tilting when both move together simultaneously and said carrier tilting on said ends when one of them becomes substantially displaced with respect to the other, and a circuit controller responsive to the tilting only of said carrier.

16. A fire detecting device comprising two concentric parallel thermostatic spirals having free ends, a carrier disposed between and fulcrumed on both free ends, said carrier being movable with said free ends without tilting when both move together simultaneously and said carrier tilting on said ends when one of them becomes sub-

stantially displaced with respect to the other, a circuit controller responsive to the tilting only of said carrier, and a stop member for limiting the amount of movement of one spiral only.

17. A fire detecting device comprising two concentric parallel thermostatic spirals having free ends, a carrier disposed between and fulcrumed on both free ends, said carrier being movable with said free ends without tilting when both move together simultaneously and said carrier 10 tilting on said ends when one of them becomes substantially displaced with respect to the other, a circuit controller responsive to the tilting only of said carrier, a stop member for limiting the amount of movement of one spiral only, and 15 means for relatively insulating that spiral from the heat which influences the other spiral.

18. A fire detecting device comprising two concentric parallel spaced thermostatic spirals having fixed inner ends and movable confronting outer ends, a carrier interposed between and carried by and tilttable on both free ends, and a mercury contactor tube carried by and tilttable with said carrier.

19. A fire detecting device comprising two concentric parallel spaced thermostatic spirals having fixed inner ends and movable confronting outer ends, a carrier interposed between and carried by and tilttable on both free ends, a mercury contactor tube carried by and tilttable with said carrier, and means for limiting the movement of the end of one spiral.

20. A fire detecting device comprising two concentric parallel spaced thermostatic spirals having fixed inner ends and movable confronting outer ends, a carrier interposed between and carried by and tilttable on both free ends, a mercury contactor tube carried by and tilttable with said carrier, means for limiting the movement of the end of one spiral, and means for relatively insulating that spiral from the heat that influences the other spiral.

21. A fire detecting device comprising a base having a recess, an insulating plate carried by said base and projecting into said recess, a pair of thermostatic spirals disposed in said recess and carried by said plate on opposite sides thereof and having free outer ends, a carrier interposed between and carried by and tilttable on both free ends, a mercury contactor tube carried by and tilttable with said carrier, stop means for limiting the free movement of the end of one of said spirals, and a heat conducting cover for said recess enclosing said spirals and disposed in heat conducting contact with one of said spirals.

22. A fire detecting device comprising a base having a recess, an insulating plate carried by said base and projecting into said recess, a pair of thermostatic spirals disposed in said recess and carried by said plate on opposite sides thereof and having free outer ends, a carrier interposed between and carried by and tilttable on both free ends, a mercury contactor tube carried by and tilttable with said carrier, stop means for limiting the free movement of the end of one of said spirals, and a heat conducting cover for said recess disposed close to one only of said spirals.

23. A fire detecting device including a pair of thermo-responsive elements, a dust tight casing enclosing said elements and isolating them from the ambient atmosphere, said elements being equally freely exposed to the atmosphere within said casing, said casing having a heat-transmitting wall exposed to the atmosphere surrounding said casing and adapted to become heated by 75

exposure to the atmosphere and to heat the interior of the casing, and one of said elements being disposed nearer than the other element to said wall and being in direct heat conducting contact with said wall so that it is more immediately responsive to the atmosphere externally of said casing.

24. A thermo-responsive device comprising a pair of thermo-responsive elements approximately equally exposed to receive externally applied heat and both approximately equally responsive to the same temperature, and a heated element

to the temperature of which said thermo-responsive elements are responsive, said heated element being in direct thermal contact with one thermo-responsive element to cause that thermo-responsive element to be more promptly responsive than the other to the temperature of said heated element, the contact being loose to permit movement of the thermo-responsive element, and signal initiating means associated with said thermo-responsive elements.
